UNITED STATES PATENT OFFICE.

LEONARD M. BEEBE, OF BEAVERTON, ILLINOIS.

HAND-GUIDE FOR WRITING.

SPECIFICATION forming part of Letters Patent No. 244,172, dated July 12, 1881.

Application filed April 11, 1881. (No model.)

To all whom it may concern:

Be it known that I, L. M. BEEBE, a citizen of the United States, residing at Beaverton, in the county of Boone and State of Illinois, have 5 invented certain new and useful Improvements in Hand-Guides for Writing; and I do hereby declare the following to be a full, clear, and exact description of the invention, such as will enable others skilled in the art to which it appertains to make and use the same, reference being had to the accompanying drawings, and to letters or figures of reference marked thereon, which form a part of this specification.

This invention relates to a simple and improved construction of hand-rests or guides for penmen; and it consists of an adjustable wire frame arranged and adapted for use in teaching penmanship, as hereinafter more fully described and claimed.

20 In the annexed drawings, which fully illustrate my invention, Figure 1 is a plan view of the device; and Figs. 2 and 3 show its application to the hand of the penman.

Like letters indicate like parts.

25 The object of the invention is to provide a simple device for the use of penmen, and especially for beginners, that will insure an easy and correct position of the hand while writing.

30 The device consists of a nickel-plated wire frame having two loops and a projecting rest or arm, the loops being connected by a brace that lies beneath the third and fourth fingers. The large loop A, which is oblong in form to 35 correspond with the shape and breadth of the hand, is placed, when in use, immediately back of the knuckles. Its lower free portion slides in a ring or guide-loop, a, that is secured to the loop A, at or near the point where it is 40 bent to form the brace B, and thus readily adjusts itself to the size of the hand. The lower portion of the wire brace B is bent into a small loop, C, for the reception of the penman's third and fourth fingers, and the con-

tinuation of the wire after making the latter 45 loop forms a projecting arm or rest, D, that extends to the right when the device is in use.

By referring to Figs. 2 and 3 it will be seen that the guide or hand rest is applied by placing the loop A on the hand back of the 50 knuckles and passing the third and fourth fingers through the loop C, so as to bring the brace B beneath, with the arm D projecting to the right. If the pen is now grasped by the thumb and first two fingers, while the third 55 and fourth fingers are turned under the upper or inner side of the loop C, the hand will be readily brought into proper position for writing.

The rest D is bent in such a manner that it 60 will not obstruct the free use of the hand so long as a correct position is maintained, but as soon as the hand is turned too much to the right its end, striking upon the table or paper, attracts the attention of the penman and reminds him that an improper position has been assumed. All tendency to carelessness on the 65 part of the pupil is thus gradually corrected.

It will be readily seen that the device not only adjusts itself perfectly to the shape and 70 size of the writer's hand, but while confining the third and fourth fingers in a set position permits the free use of the thumb and first and second fingers.

Having thus described my invention, what 75 I claim as new, and desire to secure by Letters Patent, is—

In a penman's guide or rest, the combination of the adjustable hand-loop A, having ring or guide-loop a, the brace B, finger-loop C, and 80 projecting arm D, substantially as shown and described.

In testimony whereof I affix my name in the presence of two witnesses.

LEONARD M. BEEBE.

Witnesses:

FRANCIS H. CLARK,
PRESTON CLARK.
